UNITED STATES PATENT OFFICE.

JOHN M. SHAFFER, OF DRAIN, OREGON.

CORSET.

1,247,584.

Specification of Letters Patent. Patented Nov. 20, 1917.

Application filed August 23, 1916. Serial No. 116,493.

To all whom it may concern:

Be it known that I, JOHN M. SHAFFER, a citizen of the United States, residing at Drain, in the county of Douglas and State 5 of Oregon, have invented certain useful Improvements in Corsets, of which the following is a specification, reference being had therein to the accompanying drawing.

This invention relates to improvements in 10 corsets, one object of the invention being the provision of a plurality of vertical stay members which are adapted to be connected together by a peculiar arrangement of laces, whereby the complete corset may be 15 adjusted to varying sizes by the simple manipulation of the laces, the construction further producing an exceedingly elastic and cool corset.

In the accompanying drawings:—

20 Figure 1 is a perspective view showing the corset in use.

Fig. 2 is a plan view of the complete corset.

Fig. 3 is a section taken on line 3—3 of 25 Fig. 2.

Referring to the drawings, the numerals 5 and 6 designate the outer stays which carry the respective fastening devices 13 and 14, by means of which the corset may 30 be secured in place.

A plurality of intermediate stays 7 are provided and each of the respective stays 5, 6 and 7 are provided with a plurality of eyelets 8, which when the stays are in the position as shown in Figs. 1 and 2, are alined.

The corset is made up of two sections, each section composed of a similar number of stays. The stays of each corset section are arranged in pairs. Each stay is provided with a single longitudinal series of 40 openings 8. Each pair of confronting stays of each corset section, for example, the first and second stays, the second and third stays, the third and fourth stays, etc., are adapted to be connected adjustably together in a novel manner. Two separate laces 9 and 45 11 are employed to connect these pairs of stays together, and as clearly illustrated in Fig. 2, each lace 9 and 11 has its opposite terminals passed through the end-

most openings 8 of the particular pair of stays to be adjustably secured together, being then interturned in crossed relation through the rows of openings 8 of these stays until the centermost openings 8 are 55 reached, and at this point the opposite terminals of the lace 9 as well as of the lace 11 are secured together. It will be noticed that all but the outer stays have two pairs of laces passed through each opening 8. 60 Therefore, in the act of securing the ends of any lace together the other laces are drawn upon. Again as the free terminals of all the laces are arranged to be tied together substantially at the hip line of the wearer it will be seen that the transverse adjustment of the corset may be readily accommodated by pulling in upon the terminals 10 65 and 12 at this point and letting out thereat.

The respective stays, as clearly shown in 70 section in Fig. 3, consist of a metal member 15 and the incasing fabric sheathing 16, or they may be made of any desired material that may be found more expedient.

What I claim as new is:—

In a corset, in combination a series of 75 straight strips of similar length forming stays, each stay being provided with a single longitudinal series of openings, a separate series of laces adapted to connect together the upper and the lower portions of said stays respectively, each lace of each 80 series being looped through two of the outermost openings of two stays so as to extend across the spaces between said stays 85 and being then drawn in and out of the confronting series of openings of these stays and having their terminals secured together centrally of said stays so as to be looped across the space of these stays at this point, 90 the arrangement being such that the outermost opening of each stay except the outermost stays, is adapted to have two laces passing therethrough so that the successive loops of the successive laces will form belts 95 longitudinally of said stays overlapping all of the stays.

In testimony whereof I affix my signature.

JOHN M. SHAFFER.
